UNITED STATES PATENT OFFICE.

THOMAS B. CLARK, OF HONESDALE, PENNSYLVANIA.

DESIGN FOR A CUT-GLASS DISH.

No. 40,213.

Specification for Design.

Patented Aug. 10, 1909.

Application filed June 9, 1909. Serial No. 501,216. Term of patent 7 years.

To all whom it may concern:

Be it known that I, THOMAS B. CLARK, a citizen of the United States, residing at Honesdale, in the county of Wayne and State of Pennsylvania, have invented a new, original, and ornamental Design for Cut-Glass Dishes.

Reference is to be had to the accompanying drawing, in which—

Figure 1 is an inverted plan view of a cut

glass dish embodying my invention; and Fig. 2 is a side elevation thereof.

I claim:

The ornamental design for a cut glass dish, as shown.

THOMAS B. CLARK.
